EUGENE S. HIGHT, OF PEORIA, ILLINOIS.

VARIABLE-SPEED DEVICE.

Application filed January 2, 1925. Serial No. 188.

This invention relates generally to a variable speed device, and particularly to a variable speed device by means of which differences in the R. P. M. of one shaft with relation to another shaft may be obtained, and the main object of the invention is to produce a simple and inexpensive device of the class mentioned which will function in a very positive and efficient manner.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a cross section of my improved variable speed device.

Fig. II is a vertical section of the device shown in Fig. I with parts of said device shown in elevation.

Fig. III is a front elevation of the device with the front wall of the housing thereof removed.

In the drawings, A designates my improved variable speed device which comprises a housing B composed of an annular wall 1, a front wall 2 and a rear wall 3. The annular wall 1 is provided with oppositely disposed integral flanges 4 to which said front and rear walls are secured by means of bolts, and said front and rear walls are provided with annular shoulders 5 which contact with the inner face of the annular wall 1, as shown in Fig. I. It is apparent from this construction that very tight joints are obtained between the various walls of the housing.

Formed integrally with the rear wall 3 of the housing is a bearing 6, which extends inwardly into the interior of said housing, and formed integral with the front wall 2 is a bearing 7. The bearings 6 and 7 are of course provided with openings extending longitudinally therethrough, as shown clearly in Fig. I of the drawings. 8 designates a drive shaft which is arranged for rotation in the bearing 6, said bearing being provided with a sleeve of soft material 9 which provides a better bearing surface than would be provided if the compara-

tively hard material of which the bearing is formed were caused to contact with the rotatable shaft 8. 10 designates a driven shaft which is arranged for rotation in the bearing 7, said bearing 7 also being provided with a soft metal sleeve 11 similar to the sleeve 9 already described. The drive shaft is rotated at an approximately uniform speed at all times, and the mechanism, which will now be described, is adapted to cause the speed of the driven shaft 10 to be varied with respect to the speed of the drive shaft 8.

Keyed to the drive shaft 8 at its inner end is a pinion 12 which meshes with a pair of planet wheels 13. 14 designates a member which is arranged for rotation about the exterior of the bearing 6, said member comprising a sleeve portion 15, a pair of oppositely disposed arms 16 at one of the ends of said sleeve portion, and an eccentric 17 at the opposite end of the sleeve portion. As stated above, the member 14 is capable of rotating about the bearing 6 upon which it is mounted, and for this reason said member will be referred to hereinafter as a floating member. It will be noted by referring to Fig. I that the diameter of the bearing 6 is reduced to provide a bearing surface for the member 14, and also to provide a shoulder 18 to limit the rearward movement of said member 14. It will also be seen by referring to Fig. I that a soft metal sleeve 19 is provided, which is interposed between the outer face of the bearing 6 and the member 14. The gear wheels 13, which have already been described as meshing with the pinion 12, are supported by the oppositely disposed arms 16 of the member 14, there being a stud shaft 20 associated with each individual arm 16, which stud shaft supports one of said gear wheels 13 (Fig. I). Associated with each individual gear wheel 13, preferably by being formed integral therewith, is a pinion 21, said pinions being arranged to mesh with a relatively large gear wheel 22 keyed to the inner end of the driven shaft 10.

From the foregoing it is plain that if the member 14 were held in a non-rotatable position on the bearing 6 and rotary motion were imparted to the drive shaft 8 by some suitable means, this rotary motion would be transmitted through the pinion 12 to the gear wheels 13, and because the pinions 21

rotate with said gear wheels 13 said rotary motion would be transmitted from said gear wheels 13, through said pinions 21 and gear wheel 22, to the driven shaft 10. It is apparent that because of the relative sizes of the various pinions and gear wheels the rate of speed of the driven shaft 10 would be much less than the rate of speed of the drive shaft 8, but the particular device illustrated in the drawings is intended primarily for transmitting motion to mechanisms which are operated very slowly, and while the speed of rotation of the driven shaft when transmitted in the manner described is very slow, it is the highest speed which the device illustrated is capable of transmitting.

It has just been explained how when the member 14 is held in a non-rotatable position the highest speed is transmitted to the driven shaft 10. Let it now be assumed that the floating member 14 is capable of rotating freely about the bearing 6. In this event the gear wheels 13 and pinions 21 are of course rotated about the stud shafts 20 by the pinions 12, just as they were in the case where the floating member 14 was non-rotatably held. However, the driven shaft 10 is connected to mechanism which requires some power to operate, and consequently said driven shaft and the gear wheel 22 thereon would be held immovable by said mechanism. In view of this the rotating pinions 21, instead of transmitting motion to the gear wheel 22 as in the case where the floating member was non-rotatably held, would travel idly around the stationary gear wheel 22 and would not impart movement to said gear wheel nor to the driven shaft 10 associated therewith.

The operation of the device under the two extreme conditions has been explained, and it is apparent that the rate of speed at which the driven shaft 10 is operated may be varied by retarding the rotation of the floating member 14 more or less, it being plain that as the amount of hindrance to the floating member is increased the amount of motion imparted by the pinions 21 to the gear wheel 22 is correspondingly increased, which results in an increase in the speed of rotation of the driven shaft 10. I have therefore provided my device with a retarding agency which acts upon the floating member 14, whereby rotation of said floating member may be regulated, and this retarding agency will now be described.

Associated with the eccentric 17 of the member 14 is an eccentric strap 23 in the form of an oscillatory lever which is preferably composed of a pair of parts bolted together, as shown clearly in Fig. II. The eccentric strap 23 is pivotally secured to a boss which extends inwardly from the rear wall 3 of the housing B by means of a suitable bolt or other fastening device 24, said

fastening device 24 being extended through an elongated aperture 25 in the eccentric strap 23 to permit said strap to move relatively to said fastening device. By referring to Fig. I, it will be seen that the circumferential edge portion of the eccentric 17 is seated in an annular recess 26 in the eccentric strap 23, and that a soft metal insert is located within said recess to provide an improved bearing surface for said eccentric. Arranged at the lower end of the eccentric strap 23 is a downwardly extending bifurcated portion.

Arranged adjacent to the lower end of the eccentric strap 23 is a pair of oppositely disposed cylinders 28 and 28' which are preferably formed integral with the annular wall 1 of the housing B. Each of the cylinders has associated with it an upwardly extending cavity 29. Located in each individual cylinder and arranged to reciprocate therein is a piston 30 which is connected to the downwardly extending portion of the eccentric strap 23 by a connecting rod 31, the ends of said connecting rods which are attached to the eccentric strap being extended between the legs of the bifurcated portion of said eccentric strap, and bolts are passed through said legs and through said connecting rods to pivotally connect said eccentric strap and said connecting rods together. The opposite ends of the connecting rods 31 are connected to the pistons by means of the usual wrist pins 32.

33 designates a conduit which is in communication with the interior of the cylinder 28, and 34 designates a similar conduit which communicates with the interior of the cylinder 28'. The ends of the conduits opposite to the ends thereof which communicate with the cylinders 28 and 28' communicate with a 3-way valve 35. The third conduit associated with the valve 35 is a comparatively short conduit 36 which places the interior of the 3-way valve in communication with the interior of the housing B. 37 designates the movable element of the valve 35 by means of which the flow of liquid through said valve may be controlled.

Arranged in the walls which enclose the upwardly extending cavities 29 associated with the cylinders 28 and 28' is a pair of check valves 38 (Fig. II), said check valves being spring-controlled and being adapted to open when the pistons in the associated cylinders move in one direction and close when said pistons move in the opposite direction. 39 designates a pair of air chambers which are arranged in communication with the cavities 29 through the medium of conductors 40, as shown in Fig. II. 41 designates a body of liquid, preferably oil, which is located within the housing B and within the cylinders 28 and 28' and the conductors 33 and 34. The wall 1 of the hous-

ing B is provided with an opening 42 at the upper end of said housing through which said liquid may be introduced, said opening being provided with a plug 43 whereby said opening may be sealed.

The operation of my improved variable speed devices is as follows:

Assume that it is not desired to impart any motion to the driven shaft 10 of the device.

- 10 In this event the passageway 37^a in the movable element 37 of the valve 35 will be arranged in perfect alinement with the conduits 33 and 34, and the passageway 37^b of said movable element will be in alinement 15 with the conduit 36. With the parts positioned as suggested, oil may pass from the conduits 33 and 34 through the passageway 37^a without being impeded. As the pinions 21 travel idly around the gear wheel 22 when 20 the floating member 14 is unhampered, said floating member which includes the eccentric 17 will, of course, rotate about the bearing 6. The rotation of the eccentric will cause the lower end portion of the eccentric strap 23 25 to be reciprocated, and because the pistons 30 are connected to said lower end portion of said eccentric strap by the connecting rods 31 said pistons will be reciprocated within their cylinders. Each time either of the 30 pistons is moved inwardly within its cylinder the oil within said cylinder is forced through the associated conduit 33 or 34, through the passageways 37^a and 37^b within the movable element of the valve 35, and through the 35 conduit 36 into the interior of the housing B. It is apparent from this that with the movable element 37 of the valve positioned as suggested, no material hindrance is exerted against the rotation of the member 14 and 40 said member 14 is therefore capable of rotating idly at its maximum speed.

Assume now, however, that it is desired to retard the rotation of the floating member 14 so that the driven shaft may be placed in motion and the speed of said shaft controlled. In this event the movable element 37 of the valve 35 would be turned so that a restricted passageway X is provided within the valve 35, through which restricted passageway the oil must be forced by the pistons. The result of this is that the speed of reciprocation of the pistons and of the eccentric strap 23 would be reduced and the eccentric 17 would necessarily be compelled 55 to rotate at a lower rate of speed than when the passageway X within the valve 35 is unrestricted.

It is therefore plain that the movable element 37 of the valve 35 may be turned to a 60 position where the valve 35 is closed, at which time the floating member 14 would be non-rotatably held due to the fact that it would be impossible for the pistons to reciprocate within their cylinders. Also said movable element may be moved to a position

where the valve 35 is entirely open, at which time the floating member 14 will rotate without hindrance. It is also plain that the movable element 37 of the valve 35 may be moved to positions between these two extremes to provide passageways within the valve which are more or less restricted, whereby more or less hindrance is placed on the rotation of the eccentric 17 and the associated floating member 14.

The reciprocating movement of the pistons 30 may be uneven as the direction of movement of said pistons is changed, and to reduce this unevenness of movement I employ air chambers 39. In use the oil within the cylinders rises within the cavities 29 and conductors 40 when the pistons are moved inwardly in their cylinders, thus compressing the air within the air chambers 39, after which said air gradually expands, forcing said oil downwardly in said conduits 40.

The check valves 38 are employed to permit oil to be drawn into the cylinders 28 and 28' by the reciprocating pistons therein, whereby the proper amount of oil will be maintained within the cylinders at all times.

I claim:

1. A variable speed device comprising a housing, a drive shaft, a driven shaft, planetary gearing whereby motion may be transmitted from said drive shaft to said driven shaft, a rotatable member associated with said planetary gearing, an eccentric associated with said rotatable member, a pivoted eccentric strap cooperable with said eccentric, and fluid-controlled means cooperable with said pivoted eccentric strap for retarding the operation thereof, said fluid-controlled means comprising a pair of oppositely disposed cylinders, pistons arranged for reciprocation within said cylinders, fluid conduits arranged in communication with the interiors of said cylinders, a three-way valve associated with said fluid conduits, and a fluid conduit establishing communication between the interior of said valve and said housing, said pistons being adapted to force fluid from said cylinders through the fluid conduits associated therewith to the interior of the valve and through the conduit leading to said housing and said valve being adapted to impede the passage of said fluid through said conduits.

2. A variable speed device comprising a drive shaft, a driven shaft, planetary gearing whereby motion may be transmitted from said drive shaft to said driven shaft, a rotatable member associated with said planetary gearing, retarding means adapted to retard the rotation of said rotatable member, said retarding means including fluid-controlled means comprising a pair of oppositely disposed cylinders, pistons arranged to reciprocate within said cylinders, fluid conduits

associated with said cylinders, a manually operated valve associated with said fluid conduits, said pistons being adapted to force fluid from said cylinders and through said conduits and said manually operated valve being adapted to impede the passage of fluid through said conduits, check valves associated with said cylinders whereby oil may be drawn into said cylinders, and air chambers associated with said cylinders. In testimony that I claim the foregoing I hereunto affix my signature.

10
EUGENE S. HIGHT.
